UNITED STATES PATENT OFFICE

2,550,625

SCULLING OARLOCK AND MOUNTING CLAMP THEREFOR

Carl M. Vick, Jacksonville, Fla.

Application October 15, 1948, Serial No. 54,690

4 Claims. (Cl. 9—26)

1

This invention relates to an improved form and construction of sculling oarlock and mounting clamp therefor.

An object of the invention is to provide an improved portable sculling oarlock and attaching and supporting clamp therefor which may be readily attached to the stern or transom of a boat when the same is to be used, and which may be conveniently carried in a tackle box at other times when the sculling oarlock is not being used.

Another object of the invention is to provide an improved portable sculling oarlock and mounting clamp or bracket therefor, which skill in sculling a boat may be acquired in a very short period of time.

A further object of the invention is to provide an improved sculling oarlock which will positively clamp an oar within the same while being used, and which may be readily and instantly released when it is desired to use the oar for pushing a boat or for reversing the same.

A still further object of the invention is to provide an improved form of sculling oarlock and mounting clamp therefor which may be instantly attached to the transom of a boat for sculling the same with one hand, while using the other hand for fishing, trolling, etc.

Another object of the invention is to provide an improved form and construction of portable sculling oarlock and mounting clamp therefor, which will be highly efficient in operation, and relatively inexpensive to manufacture and produce.

Another object of the invention is to provide an improved portable mounting clamp for an ordinary or conventional type of oarlock which the skilled operator may use in sculling.

Another object of the invention is to provide an improved portable mounting clamp for an ordinary or conventional type of oarlock which may be mounted on the sides of gunwales of a boat for use in rowing where oarlock ferrules are not already provided.

Other objects will appear as the description proceeds.

In the accompanying drawings which form a part of this application,

Figure 1 is a perspective view of the improved sculling oarlock and mounting clamp therefor;

Figure 2 is an edge view of the improved sculling oarlock and mounting clamp therefor, also showing the clamp attached to a transom of a boat illustrated in broken lines, and

Figure 3 is a front elevation of the improved sculling oarlock and mounting clamp therefor.

2

Like characters of reference are used throughout the following specification and the accompanying drawings to designate corresponding parts.

In carrying out the invention, there is devised and provided an improved form and construction of sculling oarlock and mounting clamp therefor including an inverted U-shape clamp body 1 adapted to be fitted over the top of a boat transom 2, one depending arm of said clamp body 1 supporting two spaced clamping screws 3 having swivel heads 4 adapted to engage the adjacent inner surface of said transom 2. A vertically disposed tubular supporting socket 5 is welded or formed at 6 to the outer surface of the other depending arm of the clamp body 1 for rotatably supporting the sculling oarlock, generally designated by the reference numeral 7.

The sculling oarlock 7 includes a depending shank portion 8 formed with an upstanding transversely apertured ear 9, and with the oppositely disposed transversely extending lugs or ears 10. A rearwardly or outwardly extending lug 11 is formed integrally with the shank portion 8, and is provided with a screw threaded vertical aperture (not shown) through which the adjusting screw 12 is adapted to extend, said screw being formed with a kerf 13 in its lower end.

The sculling oarlock 7 also comprises the outer ring portion 14 which is formed with the spaced depending ears 15 formed with transversely aligned apertures, and when said ears 15 are disposed at the opposite sides of the ear 9, a pivot pin 16 may be placed transversely through the aligned apertures. A rearwardly or outwardly extending adjusting lip or ear 17 is formed integrally with the ears 15, and will be positively engaged by the upper end of the adjusting screw 12 for selectively varying the angle at which the oarlock 7 will be used.

Oppositely extending guide lugs 18 will be formed on edges of the outer ring 14, and will terminate above the inner surface of said ring. Oppositely disposed pairs of guide lugs or ears 19 and 20 will be secured to the edges of the ring 14 at points laterally of the arcuate guide slot 21 formed in the upper portion of the ring 14, and through which the depending threaded clamping screw 22 will be reciprocably mounted. An inner ring 23 will be disposed within the outer ring 14 and in contact therewith, said inner ring 23 being provided with a threaded aperture 24 through which the threaded clamping screw 22 will be extended. The guide lugs 19 and 20 may be mounted on either the inner

ring 23 or the outer ring 14 at the option of the manufacturer. An arcuate clamping arm 25 will be supported upon the inner end of the clamping screw 22 for clamping engagement with an oar (not shown) when inserted through the said inner ring 23. An elongated angle oar support 26 will be disposed within the lower portion of the inner ring 23 for supporting the lower surface of an oar handle and to provide for self alignment of the oar while the clamping arm 25 locks against the upper surface of said oar. Since the depending guide lugs 19 and 20 and the guide lugs 18 permit rotation of the inner ring 23 within the outer ring 14 without longitudinal play, the oar will be secured in the oarlock 7 and movable for sculling, but said oar will be positively retained within the oarlock at other times unless the shank portion 6 of the oarlock is bodily lifted from the tubular supporting socket 5 for pushing or poling of the boat.

From the foregoing description, it will be apparent that the improved sculling oarlock and mounting clamp therefor may be readily attached to the transom 2 of a boat when it is to be used, and may be readily removed and stored in a tackle box or other suitable storage place when not in use.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. A sculling oarlock and mounting clamp therefor including a screw clamp adapted to clamp upon the transom of a boat, a vertically disposed tubular bearing socket on said clamp, an oarlock supporting shank detachably supported in said socket having an upstanding lug, a sculling oarlock rockably supported upon said lug comprising a stationary outer ring and an inner ring rotatably mounted in said outer ring, an oar clamping bracket mounted in said inner ring, a threaded actuating member attached to said bracket and extending through a circumferential slot in said outer ring, and an adjustable stop member carried by said oarlock supporting shank adapted to engage a stop surface on said outer ring for varying the angular position of said oarlock with respect to said supporting shank.

2. A sculling oarlock and mounting clamp therefor including a screw clamp adapted to clamp upon the transom of a boat, a vertically disposed tubular bearing socket on said clamp, an oarlock supporting shank detachably supported in said socket, said shank being provided with an upstanding lug, a sculling oarlock rockably supported upon said lug comprising a stationary outer ring and an inner ring rotatably mounted in said outer ring, an oar clamping plate located within said inner ring, a threaded actuator member attached to said plate and extending through a circumferential slot in said outer ring, said threaded actuator and circumferential slot providing means for limiting the rotary movement of said inner ring, and stop means bodily movable

4
with said shank and outer ring for varying the angular position of said oarlock with respect to said supporting shank.

3. A sculling oarlock and mounting clamp therefor including a channel shaped bracket, a screw clamp threaded in said bracket to clamp said bracket upon the transom of a boat centrally thereof, a vertically disposed tubular bearing socket on said clamp, an oarlock supporting shank detachably supported in said socket having an upstanding lug, a sculling oarlock rockably supported upon said lug comprising a stationary outer ring and an inner ring rotatably mounted in said outer ring, an oar supporting angle member secured to the inner periphery of said inner ring, an oar clamping member mounted in said inner ring, a threaded actuator shaft affixed to said member extending through a correspondingly threaded opening in said inner ring and projecting through a circumferential slot in said outer ring to provide means for limiting the rotary movement of said inner ring, and means for varying the angular position of said oarlock with respect to said supporting shank, comprising
- 20 a stop screw carried by said shank and arranged to engage a stop projection on said outer ring.

4. A sculling oarlock and mounting clamp therefor including a screw clamp adapted to clamp upon the central portion of the transom 30 of a boat, a vertically disposed tubular bearing socket on said clamp, an oarlock supporting shank detachably supported in said socket having an upstanding lug, a sculling oarlock rockably supported upon said lug comprising a stationary outer ring and an inner ring rotatably mounted in said outer ring, ears on the edges of said outer ring for preventing axial movement between said outer and inner rings, an oar supporting angle member mounted in said inner ring, a clamping plate adapted to cooperate with said angle member to clampingly engage an oar, a threaded adjustable actuator attached to said clamping plate extending through a threaded opening in said inner ring and projecting through a circumferential slot in said outer ring for limiting the rotatable movement of said inner ring, and an adjustable screw carried by said shank engageable with a surface on said outer ring for varying the angular position of said oarlock with respect to said supporting shank.
